ARCH SUPPORTER AND EXERCISER

Chester D. Adams, Lexington, Ky.

Application February 25, 1936, Serial No. 65,725

5 Claims. (Cl. 128—69)

This invention relates to an arch support and exerciser and, more particularly, comprehends a device for providing a support for the anterior metatarsal or the forepart of the foot.

5 One of the primary objects of the invention is to provide an article adapted to be applied to the toes of a foot in such a manner that pinching of the nerves, due to a fallen condition of the anterior metatarsal arch, known as metatarsalgia or Morton's toe, is relieved.

Another object of the invention is to provide an article which may be alternately gripped and released by the toes, whereby to exercise and strengthen the foot, particularly the metatarsal and longitudinal arches and ankle.

Another object is to provide an article which is highly efficient for the above purposes, and which is extremely simple in construction and inexpensive in manufacture.

20 Other and further objects will be apparent from the following detailed description and the accompanying drawing, wherein a preferred embodiment of the principles of the present invention has been selected for exemplification.

25 Figure 1 is a side view of a support constructed in accordance with the present invention.

Figure 2 is a plan view of the support as applied to the human foot.

Figure 3 is a section on line 3—3 of Figure 2, looking forwardly of the foot.

Figure 4 is a section of the device taken on line 4—4 of Figure 3.

Figure 5 is a top view.

Referring more particularly to the drawing, 35 wherein like characters refer to like parts, the support or exerciser shown therein comprises a ring or eye 10 having an arm 12 tangentially extending therefrom angularly with respect to the plane of the eye, which arm has an ex-

40 tremity 14 angularly extending or curved toward the eye side of the arm, as best shown in Figures 2 and 5. As clearly shown in Figures 2 and 3, the eye 10 of the device is adapted to receive the big or first toe of the foot, the arm 12 to extend

45 beneath the second, third and fourth toes and the curved extremity 14 to lie above the fifth toe extending rearwardly of the toe. More specifically, the respective positions of the various parts permit the extremities 10 and 14 to extend 50 over or nearly over the first and fifth metatarsal heads and the arm 12 to extend beneath the toes directly in front of the second, third and fourth metatarsal heads.

The support and exerciser herein illustrated 55 and above described is adapted for use with a

right foot and it is obvious that a support for the left foot will be merely oppositely contoured; that is, positions of eye 10 and extremity 14 with respect to the arm 12 will be reversed.

The device may be formed of any suitable material, which is preferably fairly rigid, but which may have a slight spring thereto, and in a suggested construction, as shown in Figure 4, the device may be formed of relatively heavy wire 16 having a covering 18 therefor of fabric, 10 leather, rubber or like material for comfortable contact with the foot. Preferably the material should permit of slight relative angular adjustments of the various toe engaging elements to suit varying shapes of the individual foot to provide a snug fit and obviously the device may be produced in various general sizes. 15

The device of the present invention is primarily adapted to be worn after the shoe is removed and when applied to the human foot, as 20 best shown in Figure 3, it operates to depress the first and fifth metatarsal heads and to lift the second, third and fourth metatarsal heads. In this manner, it is adapted to restore the fallen arch to normal position and relieve pain caused 25 by pinching of the nerves of the anterior metatarsal arch or forepart of the foot, particularly between the third and fourth, and fourth and fifth metatarsal heads where nerve impingement is most painful. 30

The device herein described may also be used as an exerciser, to stretch the muscles and strengthen the entire foot, particularly the metatarsal and longitudinal arches, by merely alternately gripping and releasing the device by 35 the toes.

While it is believed that from the foregoing description the nature and advantages of the invention may be readily understood, I do not limit myself to what is herein illustrated and 40 described and it is understood the principles of the present invention embrace such modified structures as fall within the scope of the following claims.

I claim:

1. A device of the character described comprising an arm having a portion thereof adapted to force the second, third and fourth metatarsal heads upwardly; and another portion thereof adapted to force the first and fifth metatarsal 50 heads downwardly, said arm carrying means for securing it to the foot. 45

2. An arch support and exerciser comprising in combination, an arm adapted to extend beneath the second, third and fourth toes in front 55

of the second, third and fourth metatarsal heads of a foot, said arm having curved extremities adapted to substantially overlie the first and fifth metatarsal heads, one of said extremities being further adapted to secure the arm in position.

3. An arch support and exerciser comprising in combination, an eye, an arm extending tangentially from the eye and out of the plane thereof, the extremity of said arm being curved 10 toward the eye side of the arm.

4. An arch support and exerciser comprising

in combination, an eye adapted to encircle a toe, an elongated arm extending from said eye a distance substantially the width of the toes of a human foot and a curved extremity for said arm.

5. An arch support and exerciser comprising in combination, a substantially rigid arm adapted to extend transversely of the toes of a human foot, and an eye integral with said arm at one end thereof for encircling one of the toes. 10
